OF ANDERSON, INDIANA, A CORPORATION OF DELAWARE

TIMER CONTROL

Application filed May 11, 1929. Serial No. 362,323.

This invention relates to ignition apparatus for internal combustion engines, and particularly to the control of ignition timing in accordance with engine operating conditions.

One of the objects of the present invention is to control the timing of the ignition so that the spark will be advanced during engine throttle movement from closed to partly open position, and so that the spark will be retarded upon further engine throttle movement, or toward wide open position.

A further object of this invention is to control the timing of the ignition in response to engine speed and also in response to engine throttle position in such manner that, during movement of the throttle from closed to partly open position, the timing of the ignition will be advanced, but upon further movement of the throttle into wide open position the timing will be retarded. In this connection it is an object of the invention to provide independently operable devices for controlling the ignition timing in response to engine speed and engine throttle position respectively so that the timing of the ignition will be the resultant of the combined effects produced, by means responsive to engine speed and by means responsive to throttle position.

Further objects and advantages of the present invention will be apparent from the following description, reference being had to the accompanying drawings wherein a preferred embodiment of one form of the present invention is clearly shown.

In the drawings:

Fig. 1 is a vertical section of an ignition apparatus embodying my invention, and in part a diagrammatic disclosure of the manner of connecting the unit with an engine carburetor, the view being that substantially indicated by the line and in the direction of the arrows 1-1 of Fig. 2.

Fig. 2 is a plan view of the ignition apparatus with the distributor cap and rotor removed.

Fig. 3 is in substance a plan view of the speed responsive means controlling the ignition apparatus and is substantially that as

indicated by the line and arrows 3-3 of Fig. 1.

Referring to the drawings, the ignition timer includes a housing 20 having a tubular shank 21 adapted to fit within a recess or socket in the engine frame, not shown, and to be secured therein in the desired position of manual adjustment by the usual means well known to those skilled in this art. The shank 21 provides a bearing for the drive shaft 22 which is connected by gearing, not shown, with a rotatable part of the engine, preferably the valve operating shaft. The upper end of the shaft 22 is provided with diametrically opposite spiral or slanting grooves 23, and fits within a recess 24 provided by the tubular lower end portion of an intermediate shaft 26. The intermediate shaft 26 is drivingly secured to a weight plate 27 supporting a centrifugal device connecting it with the interrupter mechanism as will presently appear.

The weight plate 27 carries pivot studs 28 pivotally supporting weights 29, each having a lever arm 30 which cooperates with lever arm 31 provided by plate 32 attached to the lower end of a cam carrying shaft 33. When the weights 29 move outwardly due to centrifugal force, the arm 31 and hence the cam 34 will be rotated clockwise relative to the shaft 26, in order to advance the timing of the ignition. In the disclosed form of the invention the normal form of the location of the cam 34 is clockwise as viewed in Fig. 2. Movement of the weights 29 outwardly is restricted by springs 35 each having one end attached to a weight pivot stud 28 and the other to a stud 36 attached to an arm 31 of the plate 32. Therefore, as the speed of the weight plate 27 decreases the body of the weights 29 will be moved inwardly by the spring 35 and the plate 32, and hence the cam 34 will be rotated counterclockwise in order to retard the ignition.

A weight guard plate 37 is carried by the shaft 33 and disposed over the weights 29 limiting their sidewise movements axially of their pivot studs 28 so that the weights cannot move beyond the plane of the lever arms 31.

A rotor block 40 is supported and driven by the cam carrying shaft 33, which rotates loosely about an extension 41 of the intermediate driving shaft 26. The shaft 33 is 5 journalled in a bearing 42 secured to a bearing bracket 43 which is attached to a plate 44 supported upon an angular ledge 45 provided by the housing 20. The shaft 33 is provided with a cam 34 which cooperates with a rubbing block 46 of a circuit breaker lever 47 carrying a contact 48 adapted to engage a stationary contact 49 supported by contact bracket 50 which is adjustable about the pivot stud 51 of the lever 47. A leaf spring 52 10 conducts current from a terminal bracket 53 to the lever 47 and urges the contact 48 toward the contact 49, and the rubbing block 46 toward the cam 34. The pivot post 51 is attached to the plate 44, and the terminal 15 bracket 53 is insulatingly supported by the plate 44, and is also connected by a strap or link 54 to a terminal screw 55 which is insulated from the housing 20.

A condenser 56 which is contained within a 20 case 57 is attached by a clip 58, and screw 59, to the plate 44. One of the condenser foils is electrically connected with the condenser case 57 and hence with the plate 44, and the other foil is connected with the terminal 25 bracket 53 by a conductor 60.

The stationary contact bracket 50 is adjusted by turning a stud 61 having an eccentric shank 62, by which the stud is pivotally connected with the plate 44. The head of 30 the stud 61 is received by a slot 63 in the bracket 50 and is provided with a screw driver receiving slot 64, by which the stud 61 may be turned in order to adjust the bracket 50 angularly about the pivot 51. The 35 bracket 50 is secured to the plate 44 in adjusted position by a screw 65 passing through a slot 66 in the bracket 50 and having threaded engagement with the plate 44.

The plate 44 is secured upon the annular 40 shoulder 45 provided by the housing 20 by screws 67 and nuts 68 each of which is adapted to engage a lug 69 provided by the plate 44 facilitating in clamping the plate 44 against the shoulder 45.

45 The bracket 43 for the bearing 42 is attached by rivets or other desired means to the plate 44, and provides an annular chamber 70 for receiving the thick felt or fibrous washer 71 and a thinner fibrous washer 72 having its 50 inner edge in contact with the bearing 42, which is constructed with a porous metallic structure capable of absorbing lubricant from the washer 72 and giving it out as needed to the journal of the cam carrying shaft 55 33. The lubricant for the chamber 70 is supplied through an oil cup 73 as shown in Fig. 2.

The upper end of the tubular cam-carrying shaft 33 receives a cylindrical felt pad 74 for receiving lubricant which is given out as needed to the upper extension 41 of the in-

termediate shaft 26, in order that relative movement may take place between the parts 58 and 41 with a minimum amount of friction.

The lower end of the cam carrying shaft 33 rests upon a shoulder provided by the shaft 26 and is attached to the plate 32 by a drive fit connection over the knurled part of the shaft 33. The intermediate shaft 26 is provided with a bifurcated tubular lower end 78 which is journalled loosely upon the shaft 22, and which rests at its lower end upon a collar 79, provided by swedging a washer into a shallow annular groove of the shaft 22. A spacer 80 is placed between the bottom of the plate 27 and the tubular end 78 of the intermediate shaft. Thus longitudinal movement of the shaft 22 relative to the housing 20 is prevented by reason of the collar 79 and the shank 21, the thrust washer 82 resisting the movement and taking up the play between the parts as assembled.

The intermediate shaft 26 is drivingly connected with the shaft 22 by a mechanism which is responsive to variations in fluid pressure and thereby to variations in throttle open position. A throttle 83 rotatably secured within a carburetor manifold 84 by means of a shaft 85, is operated by a cam lever 86 and a rod 87 connected to a bell crank 88 and foot button 89. The bell crank 88 is usually fixed to the floor boards of the vehicle structure as at a pivot 90 and is provided with a spring 91 which urges the throttle 83 to the closed position illustrated in Fig. 1. The cam lever 86 is formed with the advance face 92 and the retard face 93 separated by the peak 94. It is obvious that manipulation of the operating member 89 will cause the cam lever 86 and the valve 83 to rotate with the shaft 85 and that the position of the cam lever 86 will follow closely the relative position of the valve 83 with respect to the manifold 84.

Operably connecting the throttle opening mechanism with the ignition structure, there is provided a fluid pressure device or hydraulic mechanism diagrammatically illustrated in Fig. 1. The fluid pressure device in main is manifest by a driving unit 100 and a driven unit 120, which have an inter-communication by means of the tubular connection 130 substantially as illustrated. The units 100 and 120 are essentially alike in structure, in that each comprises a rigid wall 101 and 121 respectively of cup-formation having a peripheral flange 102 and 122 respectively, within which is positioned flexible diaphragm 103 and 123 respectively and a clamping disc 104 and 124 respectively, which are secured together by spinning over the flange 102 and 122 to compress the members 103 and 104 and 123 and 124 against the cups 101 and 121 as indicated at 105 and 125 respectively. Each cup member 101 and 121 are centrally apertured to receive a 130

flanged nipple 106 and 126 secured thereto and externally threaded to receive a clamping nut 107 and 127 respectively. The nuts 107 and 127 are passed over the tube 130, the ends of which are then spun outwardly as at 108 and 128 to form a seating engagement with the tapered end of the nipples 106 and 126, which, when clamped thereto by the nuts 107 and 127 respectively form a tight joint 10 impervious to the passage of the fluid medium contained therein.

The driving unit 100 differs somewhat in structure from the driven unit 120, in that a spring 109 is placed within the unit to encircle the head 110 of the nipple 106 and tends to separate the flexible wall or diaphragm 103 from the fixed wall 101, thus tending to maintain the chamber in a condition of maximum fluid content. The clamping disc 104 is centrally provided with a tubular extension 111 forming a guide for a stem 112 of a dash pot 113 positioned against the diaphragm 103. The stem 112 carries a cam follower or roller 114, and when the unit is mounted upon a bracket 115 the cam follower 114 is adapted for cooperation with the cam faces 92 and 93 of the cam lever 86 to transmit motion thereof to the diaphragm 103, and thence to the fluid content within the driving chamber 100. The bracket 115 is secured to apertured ears 116 struck from the clamping disc 104 and is attached to the manifold 84 by screws 118.

The driven unit 120, in addition to the above enumerated appointments, is provided with a plate 131 secured to a stem 132 slidably supported by a tubular extension 133 of the clamping disc 124. The plate 131 is cupped slightly at 131a to provide a retainer for seating a compression spring 134 disposed against the plate 131 and the clamping disc 124. It will be noted that unlike the driving unit 100, the chamber of the driven unit is normally maintained in a condition of minimum fluid content by the spring 134 compressing the diaphragm 123 against the fixed wall 121. When these units have been assembled as stated the chamber in each is filled with the fluid medium by which they are to function and likewise the tubular connection 130. The elements of the device are then connected together as clearly indicated in the drawings.

The timer housing 20 is formed to provide the substantially tubular extension 140, laterally apertured to provide a support for the driven unit 120. This aperture has an annular ledge 141 against which is seated the unit 120, and secured therein by clamping screws 142 and washers 143 substantially as indicated in Figs. 1 and 2. This positions the stem 132 of the driven unit in substantial alignment with the timer operating shaft 22, which is drivingly connected with certain parts thereof as will presently appear. The stem 132 is articulated with a bell crank lever

145 pivoted upon a rod 146 which extends between opposite walls of a housing 20. The bell crank lever 145 is provided with a notched angular extension 147 received by a groove 148 in the stem 132, the notch of the part 147 receiving the portion of reduced diameter of the member 132 defining the bottom of the groove 148.

The bell crank lever 145 provides arms 149 encircling the intermediate shaft extension 78, and each arm 149 is provided with an angular extension 150 having a notch which receives the outwardly extending flange 151 of a collar 152 which is slidable along the intermediate shaft extension 78. The collar 152 supports diametrically opposite studs 153, each of which has a portion received by one of the two diametrically opposite longitudinal slots 154 provided by the intermediate shaft extension 78. Each stud 153 is of such length as to extend through the slot 154 and be received and movable along the slot 23 of the shaft 22.

As illustrated the shaft 22 is provided with the reduced end portion 155 to which is secured the coil spring 156 one end of which is received by the slot 154 of the shaft extension 78. This spring 156 is biased so as to urge the shaft extension 78 in a counterclockwise direction with respect to the shaft extension 155. The function of this spring is to assist in restoring to normal the relation between the intermediate shaft 26 and the drive shaft 22. As the collar 152 moves from the normal of full line position shown in Fig. 1 to the dotted line position the shaft 26 will rotate in a clockwise direction relative to the shaft 22, as viewed in Fig. 2. This relative rotative movement is resisted by spring 156. When the collar 152 moves downwardly the shaft 26 tends to rotate counterclockwise relative to shaft 22 and this movement is assisted by the spring 156.

The timing of the ignition control in response to the throttle opening or position of the valve 83 is accomplished in the following manner. The throttle 83 is operated by pressing the pedal 89, which causes the bell crank lever 88 to move in a counterclockwise direction and the cam lever 86 in a clockwise direction. During a portion of the movement of the valve 83 from closed toward open position, the roller 114 is in engagement with the advanced cam surface 92 which is so shaped as to lift the roller 114 and cause the dash pot 113 to move inwardly to compress the fluid medium within the driving chamber 100. The fluid medium within the chamber being compressed will find its way out through the nipple 106 and by way of the tubular connection 130 into the driven chamber 120, where the medium exerts pressure upon the diaphragm 123 and disc 131 moving the stem 132 toward the left of the illustration, which causes the bell crank lever 145 to pivot about 130

the pin 146 and move the collar 152 downwardly along the shaft extension 78. As before stated the shafts 22, 26 and 33 are so interconnected that the downward movement of the collar 152 upon the shaft extension 78 will cause an advance in the time relation between the engine cycle and the interrupter cycle.

The ignition timing continues to be advanced as the throttle 83 is moved from closed toward open position until a certain open position of the throttle has been reached beyond which it is not desirable to advance the timing of the ignition in response to further opening of the throttle. This point of throttle opening is marked by the crest point or peak 94 joining the advance cam surface 92 with the retard cam surface 93. When this predetermined position of the throttle has been reached the crest portion 94 of the cam lever 86 will be directly under the roller 114. Further movement of the throttle 83 toward open position is produced by further movement of the cam lever 86 in a clockwise direction. During this forward movement the cam surface 93 of the lever 86 will engage the roller 114, and as the lever 86 moves clockwise the stem 112 will be retracted under the action of the spring 109, which releases the pressure upon the fluid content of the chamber 100 and allows the spring 134 in the driven unit to exert itself upon the diaphragm 123 and move the fluid medium through the tubular connections 130 to the unit 100 thereby establishing an equilibrium of pressure within the system. This retracted movement of the stems 112 and 113 acting upon the bell crank lever 145 and likewise upon the shafts 22 and 26, cause a retarding of the spark responsive to further throttle opening position.

When pressure upon the foot pedal 89 is released the spring 91 is permitted to move the pedal 89 upwardly which through the linkage of the mechanism tends to close the throttle 83 and with it returns the cam lever 86 toward the normal position. During this movement the functions of the above described unit are performed in a reverse order. That is, as the valve 83 moves from wide open to closed position the ignition timing will first be advanced and then retarded. It will be noticed that the device which controls the timing of the ignition in response to throttle open position operates independently of the speed responsive means, but that both devices operate cumulatively or differentially dependent upon the conditions under which the vehicle is driven or the ignition apparatus is used.

While the form of embodiment of the present invention as herein disclosed, constitutes a preferred form, it is to be understood that other forms might be adopted, all coming

within the scope of the claims which follow.

What is claimed is as follows:

1. Ignition apparatus for internal combustion engines comprising, an engine driven circuit interrupter, means responsive to engine speed for controlling the interrupter to advance the timing of the ignition, and fluid pressure means responsive to engine throttle position for so controlling the interrupter that ignition timing will be advanced during engine throttle movement from closed to partly open position, and the ignition timing will be retarded during further throttle movement toward full open position. 70 75

2. Ignition apparatus for internal combustion engines comprising, a circuit interrupter including a breaker lever and an engine driven cam, speed responsive means for varying the time relation of the cam to the engine in order to advance the time of the engine as the speed increases, and hydraulic means responsive to engine throttle position for varying the position of the breaker lever relative to the cam during engine throttle movement from closed to partly open position, so that the ignition timing will be advanced and thereafter be retarded upon continuing throttle movement toward further open position. 80 85 90

3. Ignition apparatus for internal combustion engines, comprising, an engine driven circuit interrupter, and fluid pressure means responsive to engine throttle position for controlling the interrupter, so that ignition timing will be advanced during movement of the engine throttle from closed to partly open position, and so that the ignition timing will be retarded during further throttle open movement. 95 100

4. Ignition apparatus for internal combustion engines comprising, a circuit interrupter including a circuit breaker lever, and an engine operated cam responsive to engine throttle position for varying the position of the breaker lever relative to the cam and fluid pressure means transmitting motion of the engine throttle to the circuit interrupter, so that the ignition timing will be advanced during engine throttle movement from closed to partly open position, and thereafter be retarded upon further throttle open movement. 105 110 115

5. The combination with an internal combustion engine having a rotatable throttle valve and a shaft for operating the same, of an engine operated circuit interrupter and fluid pressure means for controlling the circuit interrupter in response to throttle position. 120

6. The combination with an internal combustion engine having a rotatable throttle valve and a shaft for operating the same, of an engine operated circuit interrupter, and means for controlling the circuit interrupter in response to throttle positions and comprising 125 130

ing, a cam lever connected with the throttle shaft, and a cam follower associated with the said lever and fluid pressure transmission means associated with said cam follower for varying the time relation between the engine cycle and the interrupter cycle.

7. The combination with an internal combustion engine having a rotatable throttle valve and a shaft for operating the same of an engine operated circuit interrupter, and means for controlling the circuit interrupter in response to throttle positions and comprising, a cam lever connected with the throttle shaft, and fluid pressure means associated with the circuit interrupter for varying the time relation between the engine cycle and the interrupter cycle.

8. The combination with an internal combustion engine having a rotatable throttle valve and an operating shaft therefor, of an engine operated circuit interrupter including a circuit breaker lever and an engine driven cam, and means for varying the angular relation between the breaker lever and cam, comprising a cam lever connected with the throttle shaft, and fluid pressure means associated therewith and with the breaker lever support.

9. The combination with an internal combustion engine having a rotatable throttle valve and an operating shaft therefor, of an engine operated circuit interrupter and means for controlling the circuit interrupter in response to throttle positions, comprising, a cam lever connected with the throttle shaft, and fluid pressure means supporting a cam follower and associated with the circuit interrupter for varying the time relation between the engine cycle and the interrupter cycle.

10. The combination with an internal combustion engine having a rotatable throttle valve and an operating shaft therefor, of an engine operated circuit interrupter and means for controlling the circuit interrupter in response to throttle positions, comprising, a cam lever connected with the throttle shaft, and fluid pressure means supporting a cam follower and associated with the circuit interrupter for varying the time relation between the engine cycle and the interrupter cycle, said fluid pressure means transmitting movement of the engine throttle to predetermine angular associations of the circuit interrupter and cam.

11. The combination with an internal combustion engine having a throttle valve and an operating shaft therefor, of an engine operated circuit interrupter, including a circuit breaker lever, and a cam for operating the same, means for varying the angular relation between the breaker lever and the cam, and comprising a cam lever connected with the throttle shaft, fluid pressure means associated with the breaker lever and trans-

mitting motion of the throttle valve to angular displacement between the circuit breaker lever and the cam, and means for altering the relative movement between the throttle valve and fluid pressure means.

12. The combination of an internal combustion engine having a throttle valve and a shaft for operating the same, with an engine operated circuit interrupter, and means for controlling the circuit interrupter in response to throttle position, comprising a movable member associated with the circuit interrupter for varying the time relation between the engine cycle and the interrupter cycle, a spring for moving the member into ignition retarding position, a cam connected with the throttle shaft, and fluid pressure means cooperating with said cam to move said member into ignition advancing position, whereby the time relation between the engine cycle and interrupter cycle will be altered according to throttle open position.

13. The combination with an internal combustion engine having a rotatable throttle valve and a shaft for operating the same, of an engine operated circuit interrupter and fluid pressure means for controlling the circuit interrupter in response to throttle position, said fluid pressure means comprising a pair of sealed chambers and a connecting passage, one wall of each chamber being flexible and biased toward a normal position.

14. The combination with an internal combustion engine having a rotatable throttle valve and a shaft for operating the same, of an engine operated circuit interrupter and fluid pressure means for controlling the circuit interrupter in response to throttle position, said fluid pressure means comprising a driving chamber and a driven chamber each provided with a flexible wall, means providing inter-communication of one chamber with the other, means in the driving chamber for displacing the movable wall thereof, and means within the driven chamber for transmitting the said displacing movement to said circuit interrupter.

15. The combination with an internal combustion engine having a rotatable throttle valve, a shaft for operating the same, and an engine operated circuit interrupter, of fluid pressure means for controlling the circuit interrupter in response to throttle position.

16. The combination with an internal combustion engine having a rotatable throttle valve, a shaft for operating the same, and an engine operated circuit interrupter, of fluid pressure means for controlling the circuit interrupter in response to throttle position, said fluid pressure means comprising a pair of communicating collapsible chambers substantially filled with a liquid medium.

17. The combination with an internal

combustion engine having a throttle valve and a member for operating the same, of an engine operated circuit interrupter and fluid pressure means for controlling the timing of said interrupter in response to throttle position.

18. The combination with an internal combustion engine having a throttle valve and a member for operating the same, of an engine operated circuit interrupter, and fluid pressure means responsive to engine throttle position for controlling the interrupter, so that ignition timing will be advanced during movement of the engine throttle from closed to partly open position, and so that the ignition timing will be retarded during further throttle open movement.

19. The combination with an internal combustion engine having a throttle valve and a member for operating the same, of an engine operated circuit interrupter, including a circuit breaker lever and an engine driven cam, and means for varying the angular relation between the breaker lever and cam, comprising a cam lever connected with the member, and fluid pressure means associated therewith and with the breaker lever support.

20. In ignition apparatus for internal combustion engines, fluid translation means comprising, means responsive to engine throttle position for so controlling the interrupter that ignition timing will be advanced during engine throttle movement from closed to partly open position, and so that the ignition timing will be retarded during further throttle movement toward full open position.

21. In ignition apparatus for internal combustion engines the combination comprising, a cam lever connected with the throttle, a cam follower associated with the said lever, and fluid-pressure translation means associated with said follower for varying the timer relation between the engine cycle and the interrupter cycle.

22. In ignition apparatus for internal combustion engines, fluid-pressure means for controlling the circuit interrupter in response to throttle position, said fluid pressure means comprising in combination, a driving chamber and a driven chamber each provided with a flexible wall, means providing inter-communication of one chamber with the other, means in the driving chamber for displacing the movable wall thereof, and means within the driven chamber for transmitting the said displacing movement to said circuit interrupter.

23. In testimony whereof I hereto affix my signature.

JAMES L. ARTHUR.
